UNITED STATES PATENT OFFICE.

PAUL MAUSER, OF OBERNDORF-ON-THE-NECKAR, GERMANY.

FIREARM.

988,202.

specification of Letters Patent. Patented Mar. 28, 1911.

Application filed October 19, 1910. Serial No. 587,861.

To all whom it may concern:

Be it known that I, PAUL MAUSER, Royal Privy Commercial Councilor, a subject of the King of Würtemberg, residing at Oberndorf-on-the-Neckar, in the Kingdom of Würtemberg, Germany, have invented certain new and useful Improvements in and Relating to Firearms, of which the following is a full, clear, and exact description.

10 In the employment of modern automatic loading firearms for military purposes it has latterly been found to be necessary to inclose the barrel in the stock for its entire length, that is to say to provide it throughout its 15 whole length with what is termed hand protection, in order to protect the hands of the user from burning. It has, however, been found that with long-continued quick firing the stock begins to smoke and even to carbonize, so that means are required to insulate the stock (which is itself used as a heat insulating means) from the action of the heat of the barrel. Means serving this object of air cooling or heat insulation for the stocks 20 of firearms affording protection for the hands is illustrated by way of example in the accompanying drawing, in which:

Figure 1 shows an embodiment of the invention in longitudinal elevation, partly in 30 section. Fig. 2 is a vertical cross section on the line A—A in Fig. 1; and Fig. 3 illustrates another constructional form of the invention in longitudinal elevation, partly in section.

35 In accordance with the invention, a tube *r* is arranged inside the wooden stock over the barrel *l* which is inclosed below throughout its entire length by the stock *s* and above by the protecting wood casing *h*; the front end 40 of this tube *r* bears against the front sight support and its rear end bears against the foot of the back sight. This tube *r*, in which the barrel is entirely free, is fluted in such a manner that owing to the space formed between the wooden stock and the tube, the air 45 is able to pass between the barrel and the stock and the hand protecting casing.

The tube *r* is formed with discharge 50 apertures *r*¹ which place it in communication with the flutings and also with longitudinal recesses *s*¹ in the stock which are formed beneath the tube *r*. On its under side the stock itself is formed with oblique air apertures *s*² which establish communication between the longitudinal recesses *s*¹ and the atmosphere. In this manner efficient cooling

of the barrel is provided for, the openings in the tube enable the hot air to issue into the wide recesses in the stock, while the barrel itself does not become so rapidly heated, because it is entirely free in the tube, and deterioration of the barrel owing to the friction of the bullet is considerably reduced.

The barrel and the tube constitute a very 65 rigid whole and impart adequate strength to the stock so that exactitude of aim is increased, because otherwise, when greatly heated, the stock is distorted owing to the fact that the fibers of the wood do not run 70 exactly parallel and this causes distortion of the barrel, and thus impairs the accuracy of aim. All these defects are almost entirely avoided in the present arrangement by the combination of the stock with a tube arranged inside it and inclosing the barrel, this tube being provided with ventilating ports.

In the construction illustrated in Fig. 3 the tube *r* which is arranged over the barrel *l* is cut with a screw thread *e* on its rear end where it is screwed onto a correspondingly threaded portion of the barrel. In order to strengthen it, the threaded part *e* of the tube *r* is preferably surrounded by a 85 steel ring *f* or the like. The length of the tube *r* is such that between its front end and the front sight support, play is provided so that in firing a free linear expansion of the outer tube can take place.

What I claim and desire to secure by Letters Patent of the United States is:

1. A firearm including a barrel, a fluted tubular member arranged around said barrel and inclosing a space between the barrel and the inner face of said fluted tubular member, a stock and a hand protecting casing arranged around said tubular member, openings in said tubular member and transverse passages extending through said stock.

2. A firearm including a barrel, a fluted tubular member arranged around said barrel and inclosing a space between the barrel and the inner face of said tubular member, openings in said tubular member, a stock formed with recesses, a hand protecting casing, said stock and hand protecting casing arranged around said tubular member and transverse passages extending through said stock leading from the exterior into said recesses.

3. A firearm including a barrel formed with a screw thread on the outer periphery

thereof, a fluted tubular member arranged around said barrel and inclosing a space between the barrel and the inner face of said fluted tubular member, a screw thread formed on said tubular member and engaging with the screw thread on said barrel, openings in said tubular member, a stock, a hand protecting casing, said stock and hand protecting casing arranged around said

tubular member, and transverse passages 10 extending through said stock.

In witness whereof, I have hereunto signed my name in the presence of two subscribing witnesses.

PAUL MAUSER.
